UNITED STATES PATENT OFFICE:

CHARLES O. RYBERG, OF BROCKTON, MASSACHUSETTS.

HEEL-BUILDING MACHINE.

989,059.

Specification of Letters Patent. Patented Apr. 11, 1911.

Application filed March 8, 1910. Serial No. 548,066.

To all whom it may concern:

Be it known that I, CHARLES O. RYBERG, of Brockton, in the county of Plymouth and State of Massachusetts, have invented certain new and useful Improvements in Heel-Building Machines, of which the following is a specification.

This invention relates to heel building machines.

10 A relatively large proportion of the lifts which are assembled to form heels are composed of relatively small pieces or sections laid edge to edge, the purpose being to utilize in this way small pieces of leather which 15 would otherwise be too small for producing complete lifts.

One purpose of the present invention is to provide a heel building machine comprising a plurality of closely organized units, 20 each unit including a complete mechanism for cutting and assembling relatively small pieces of leather to form composite lifts thereof.

In carrying out the invention the cutting 25 dies of the several units are provided with cutting edges having the outline of a heel and with interior cutting blades dividing the space within the outline into sections of various shapes and sizes. The arrangement of 30 the interior dividing blades of each unit is unlike the arrangement of the blades of the other units and the machine thus presents cutters adapted to receive pieces of leather of a great variety of shapes and sizes and to 35 utilize said pieces with a minimum of waste material. For example, the operative upon picking up a piece at random may select from the several cutting devices a cutting section closely resembling the piece in hand 40 and with the aid of a mallet a section of a lift may be severed from the piece by laying the piece upon the appropriate cutting edges and striking it with the mallet.

In addition to the wide variety and shapes 45 of cutting devices the invention provides means for pivotally supporting the several cutting dies upon axes intersecting the dies and extending transversely thereof. In other words, the dies are mounted upon trunnions 50 and are adapted to be inverted.

In putting the device into practice the pieces of leather are laid upon the upper end of the cutting edges and the blow of the mallet is given while the work is in this position. After the several divisions of the

lift have been cut and depressed into the die by the mallet the die may be inverted and the work ejected downwardly from the die into an appropriate receptacle. For this purpose the invention includes an expandible 60 mold provided with spring devices by which it is normally contracted. The upper end of the mold is provided with converging walls which force the several pieces or sections toward each other when the pieces are 65 pressed into the mold. The pieces thus assembled may be fastened together by glue or cement in the manner hereinafter explained.

As a further development of the invention 70 the cutting dies are provided with cutting edges at both ends, said cutting edges being oppositely disposed so that either end of the die may cut and receive the work. An advantage of providing double-edged cutting dies is that the arrangement of the interior dividing blades at one end may be unlike the arrangement at the other end, with the result that the dividing lines between the sections of one lift may not register with 80 those of the contiguous lift. When first one end and then the other end of a die of this character is employed to form a column of composite lifts of an alternate structure the fastening together of the lifts by cement is 85 rendered entirely efficient. It may be desirable to provide a whole life or one-piece lift, to hold together the several sections of a composite lift, and for this reason the interior dividing blades may be omitted from 90 one end of the die. The several units thus constructed and arranged may be combined in a compact mass upon a bench or bed-plate. According to the arrangement illustrated the expandible molds are arranged 95 vertically in a bed-plate and are open at the bottom so that the lifts inserted at the top may be forced out at the bottom. If desired each mold may be provided with a chute to receive the lifts forced out at the 100 bottom, said chute being detachably arranged so that it may be removed when it becomes filled with lifts.

The invention further provides abutments for supporting the dies against the blow of the mallet and coacting projections extending laterally from the dies which are adapted to be seated upon said abutments. Each cutting die is mounted in a carrier by which it may be moved to its seat upon 110

the abutment and by which it may be elevated to permit the inverting of the die on its trunnions. The carriers may be normally elevated by suitable springs and may 5 be depressed by treadles.

The drawings illustrate two different forms of construction of cutting dies. According to one form the cutting edges at the opposite ends of the die are permanently related to each other, whereas in the other form the cutting edges at the two ends are arranged in a holder or clamp and may be removed to permit the substitution of other cutting edges. In the latter instance the holder or clamp constitutes an element of the die carrier. In all of the forms illustrated the cutting dies are provided with ejectors by which the lifts or sections thereof may be ejected. The ejectors are permanently, but movably, arranged within the dies and are adapted to be moved in opposite directions so as to eject the work first from one end and then from the other end. The provision of these double-acting ejectors is not disturbed in any way by variation in the arrangement of the cutting blades at the two ends of the die.

Of the accompanying drawings which form a part of the specification, Figure 1 represents a top plan view of a heel building machine including a plurality of independent heel building units. Fig. 2 represents a front elevation thereof with one of said units in vertical section. Fig. 3 represents a horizontal section on line 3-3 of Fig. 2. Fig. 4 represents a vertical section of a machine in a plane extending from front to rear. Fig. 5 represents a vertical section in a front to rear plane including the upper end of an expansible mold and one form of cutting die. Fig. 6 is a section similar to Fig. 5 showing the die in another position. Fig. 7 is a section similar to Fig. 5 showing the cutting die depressed. Fig. 8 illustrates a pair of ejectors in perspective. Fig. 9 is a vertical transverse section, including the upper end of an expansible mold and a cutting die having removable blades. Fig. 10 is a section similar to Fig. 9 showing the die in another position. Fig. 11 is a section similar to Fig. 9 showing the die depressed. Fig. 12 represents in perspective a split clamp or holder for the removable cutters. Fig. 13 represents in perspective a pair of complementary cutters. Fig. 14 represents in perspective a set of ejectors including a single member for one end and complementary sections for the other end of a double-edged die. Fig. 15 represents a top plan view of a lift. Fig. 16 represents a horizontal section of an expansible mold taken on line 16-16 of Fig. 5.

The same reference characters indicate 65 the same parts wherever they occur.

Referring first to Figs. 1 and 2 it will be observed that a plurality of independent cutting and assembling units are arranged in close relation in a bench or frame which includes a bed-plate 20 and supporting legs 70 21. The bed 20 is provided with vertical openings 22 over which relatively heavy plates or blocks 23 are arranged. The upper surfaces of the plates constitute seats or abutments for the cutters hereinafter described. Each plate is formed with an opening 24, which is substantially heel-shaped but considerably larger than a heel lift. Each plate 23 is provided with bosses 25 in which are arranged vertically movable plungers 26. The plungers are arranged at opposite sides of the opening 24 and their upper ends are provided with trunnions 27. The trunnions are in the form of screws and they are adjustable toward and from each other. The screws serve as pivotal supports for a cutting die and the die may be moved into the opening 24 by depressing the plungers 26. The plungers are normally elevated by springs and may be manually depressed against the tension of the springs. The springs are indicated at 28, and are coiled on the plungers and compressed between the bosses 25 and the heads 29 at the upper ends of the plungers. 95 Any preferred form of manually operative device may be provided for depressing the plungers. As shown by Figs. 2 and 4 the lower ends of the plungers are connected to rods 30 and the rods are in turn connected to arms or levers 31. The two arms 31 for each unit are formed upon, or otherwise rigidly secured upon a rock-shaft 32. The rock-shafts are mounted in bearings in fittings 33 adapted to be secured to the floor. The rock-shafts all extend from front to rear of the machine and their front ends are provided with treadles 34. For the convenience of the operative the treadles may be positioned in staggered relation as shown by Fig. 3. The connecting rods 30 may be provided with turn buckles 35 and the plungers 26 may thereby be adjusted so that the trunnions 27 of each unit shall be in alinement.

The cutting die shown by Figs. 5, 6, and 7 has cutting edges at both ends, said cutting edges being oppositely disposed so as to be adapted to cut by movement in opposite directions. The cutting edges are indicated respectively at 36 and 36' and their shape is that of the outline of a heel as shown by Figs. 1 and 6. These cutting edges are afforded by blades which are integral or otherwise rigidly and permanently associated with each other. The space within the outline of the cutting edges 36 and 36' may be occupied by interior cutting blades arranged at various angles, that within the cutting edge 36 being indicated at 37 and that with 130

in the cutting edge 36' being indicated at 37'. In this form of die there is a single interior cutting blade at each end which divides the space into two sections. The blades 5 37 and 37' are preferably arranged to produce sections whose seams when the sections are assembled shall not coincide with the seams of contiguous lifts. The cutting die is provided with a projecting portion adapted 10 to be seated upon the top plate or abutment 23. In the form shown by Fig. 5 the projecting portion of the die is in the form of a flange 38 extending laterally from the cutting blades between the opposite edges of 15 the die. The diameter of the opening 24 in the plate 23 is such as to admit the end of the die, but to coat with the laterally extending faces 38' of the flange 38. When the operative wishes to cut a lift or a section 20 of a lift he depresses the treadle connected with the desired cutting die so as to place the flange 38 upon its abutment. While the die is thus seated a piece of leather is placed upon the cutting edge which is uppermost 25 and the mallet may be brought down upon the work to cut a piece of the desired shape. When the entire space within the marginal cutting edge has been filled with one or more pieces of leather the piece or pieces may be 30 transferred from the die into the expansible mold attached to the under side of the plate 23. The method of transferring the work consists in releasing the treadle so that the springs 28 may elevate the die from its abutment 35 so that the die may be inverted upon its trunnions 27. After the die has been inverted the treadle may be again depressed to seat the flange 38 upon its abutment. The work which is then at the lower end of the 40 die is ejected by downward pressure upon its upper surface. For the purpose of transferring the work from the die to the expansible mold the die is provided with ejectors which are movable in opposite directions and 45 are adapted to eject the work from either end of the die. The ejectors included in Fig. 5 comprise plates or blocks 39 and 39', which are of the same general shape as the space within the blades by which they are 50 surrounded. The plate 39 at one end of the die and the corresponding plate 39' at the opposite end of the die may be rigidly connected with each other by a stud or shank 40 (see Fig. 8). As shown by Fig. 5 a trans- 55 verse partition 41 divides the die between its ends, and the studs 40 extend loosely through the partition. The partition serves to strengthen the die, and serves also as means for preventing the ejectors from 60 dropping out of the die. In this form the dividing blade 37 at one end of the die is parallel to the dividing blade 37' at the opposite end. The ejector plates 39 are therefore similar in shape to the ejector plates 65 39'. The division between the sections of

one lift is therefore at an angle to the division between the sections of the lifts which are prepared by the opposite end of the die because the die is inverted for each operation so that the successive lifts are prepared 70 alternately by first one end and then the other end of the die. The work-engaging surfaces of the ejectors are so spaced with relation to the length of the die that they may be depressed to the horizontal plane of 75 the lower edge of the die, and at the same time the ejectors at the upper end of the die are depressed below the upper edge of the die slightly more than the thickness of a lift. The ejectors may be actuated by striking the 80 upper surfaces individually or by first laying on the upper end of the die the pieces of leather which are to form the next lift, and by effecting ejection of the previous section by the blow which severs the new 85 section.

In the form shown by Figs. 9 to 14 the cutting blades are removably secured in a contractible clamp or holder. In this form the holder comprises two clamping members. 90 As shown by Fig. 12 each clamping member is formed with flanges 42 and 42' extending longitudinally and with a transverse partition or abutment 43. The flanges 42 combine to form an outline like that of a heel, but the clamping members are divided longitudinally in a plane at one side of the center of the line. The larger of the two clamping members is provided with sockets 44 which are adapted to receive the ends of the trunnions 27. The clamp or holder may be considered as a part of the die carrier inasmuch as the cutting blades may be removed without removing the clamp from the trunnions. As shown by Fig. 9 two complementary cutting blades 45 and 45' are arranged in the upper end of the clamp or holder so that the cutting edges project above the flanges 42 and so that the bottom edges are seated upon the partitions or abutments 43. The cutters 45 and 45' are illustrated separately by Fig. 13. The two pieces of leather produced by these cutters combine to form a lift. The abutting walls of these cutters may be provided with transverse holes for the reception of a connecting bolt 46. In the lower end of the holder as shown by Fig. 9 is arranged a cutter 45' which bears a relation to the cutters 45 and 45' similar to the relation existing between 110 the cutters 36 and 36' of Fig. 5. The cutter 45', however, is not divided by interior blades but is adapted to sever an entire lift consisting of a single piece of leather. The two sections of the clamp or holder are 115 formed with holes extending transversely through the partitions 43 for the reception of the clamping bolt 47. By means of a nut 48 screw-threaded upon one end of the bolt 47, and a head 49 on the opposite end of 120

the bolt the two sections of the clamp may be drawn together to clamp the several cutters between the flanges 42 and 42'. The sections of the lift formed by the cutters 45 and 45^a are slightly separated when they are severed because of the separation of the adjacent cutting edges of the abutting walls of said cutters. It is desirable that the cutter 45' be adapted to cut a lift equal in size 10 to the sectional lift produced by the cutters 45 and 45^a when the sections of that lift are brought together. The width of the cutter 45' is therefore slightly less than the aggregate width of the cutters 45 and 45^a, and 15 for this reason pieces 50 are inserted between the lower flanges 42' and the cutters 45' to effect equal clamping of the upper and lower cutters when the two sections of the clamp are compressed. The manner of 20 operating this form of die is the same as that prescribed for operating the die shown in Fig. 5, and the ends of the flanges 42 and 42' coat with the upper surface of the plate or abutment 23 to support the cutters 25 against the blow of the mallet. The cutters 45, 45^a and 45' are provided with ejectors 51, 51^a and 51' (see Fig. 14). The ejectors 51 and 51^a which constitute complementary sections are connected with the ejector 30 51' which entirely fills the space in the cutter 45'. For this reason the partitions or abutments 43 of the clamp are cut away to provide sufficient space for the longitudinally movable rods 52 by which the ejectors 35 are connected.

The preferred manner of assembling the lifts produced by the cutters shown in Fig. 9 is to first sever an entire lift by the cutter 45' and then deposit the lift in the expandable mold beneath the plate 23. The cutters 51 and 51^a are then used to sever complementary sections of a lift, and a layer of glue or cement is then applied to the upper surface of the sections in the cutters. When 40 the cutters have been inverted and the sections have been ejected the glue-laden surfaces are laid in contact with the one-piece lift previously ejected. By thus depositing first an entire lift without glue, and then a 45 sectional lift with glue the lifts become assembled in a column of which the sections of each sectional lift may adhere to an entire lift, and the column is composed of pairs of glued lifts.

55 The expandable mold is shown by Figs. 2, 4, 5, 9, and 16 and comprises three sections indicated respectively at 53, 54 and 55. The sections 53 and 54 are curved as shown by Fig. 16 and the section 55 is preferably 60 straight and engages the edge of the lift which becomes the breast of the heel. Any preferred form of yielding means may be provided for normally compressing the sections 53, 54 and 55 for the purpose of assembling the several pieces of the sectional 65

lifts so that their complementary edges shall be brought together. The upper ends of the sections 53, 54 and 55 are beveled as shown by Figs. 5 and 9 so that the compressing of the edges of the lifts is occasioned by depressing the column of lifts. The several sections of the mold may be provided with lugs or ears 56 extending laterally to receive screw bolts 57. As shown on the drawings the bolts extend through the ears 56 and 75 also through the plate 23.

A convenient form of yielding device for compressing the sections of the mold consists of one or more strips 58 of soft wire or other flexible material, and a helical spring 80 59 connecting the ends of each strip. The strip 58 and spring 59 are arranged so as to surround the mold, the strip 58 embracing the curved sections 53 and 54 and the spring 59 embracing the breast section 55. The adjacent edges of the curved sections 53, 54 may be provided with ears 60 and 61 to receive a set screw 62. The set screw is threaded in the ear of one section and abuts against the ear of the other section to limit 90 the closing of said section.

As shown by Figs. 2 and 4 the lower end of the expandable mold is formed to receive one end of a chute 63. The chute may be formed of sections 64, 65 and 66 corresponding to the sections 53, 54 and 55. The chute may likewise be provided with yielding means such as strips 67 and springs 68 corresponding respectively to the strips 58 and springs 59. When the chute becomes filled 100 it may be removed from the mold and be replaced by an empty chute, or if desired the chute may be left in the position shown and the lifts may be permitted to drop from the lower end upon the floor or into a receptacle provided therefor.

Having thus explained the nature of my said invention and described a way of constructing and using the same, although without attempting to set forth all of the forms 110 in which it may be made or all of the modes of its use, what I claim is:—

1. In a heel building machine, a contractible die holder having transverse abutments, a plurality of separable cutting dies arranged in said holder and seated on said abutments, means for compressing said holder to secure said cutting dies, a bed, and a carrier for carrying said holder to and from said bed, said die holder being pivotally mounted in said carrier so as to be seated on said bed with either end uppermost.

2. In a heel building machine, a die holder consisting of two clamping members and means for contracting them, transverse abutments on said clamping members, a plurality of separable cutting dies arranged and clamped one against another in said holder and seated on said abutments, a carrier for 125

said holder, and a bed arranged to receive and rigidly support said holder to receive the blow of a mallet.

3. In a heel building machine, a die holder 5 consisting of two clamping members and means for contracting them, said clamping members having clamping flanges and transverse abutments between the ends of the flanges, a plurality of separable dies 10 ranged in each end of said holder and seated upon opposite sides of said abutments, and clamped one against another

by said flanges, the dies in one end being oppositely disposed with relation to those in the other end, and a carrier for said die 15 holder, said holder being pivotally mounted in said carrier so as to be adapted to present the dies at either end for operation.

In testimony whereof I have affixed my signature, in presence of two witnesses.

CHARLES O. RYBERG.
